REFRIGERATOR SHELF

Verlos G. Sharpe, Dayton, Ohio, assignor to General Motors Corporation, Detroit, Mich., a corporation of Delaware

Application October 8, 1956, Serial No. 614,627

13 Claims. (Cl. 312—351)

This invention relates to a refrigerator cabinet and particularly to a shelf arrangement therefor.

I am aware of the fact that others have provided swingably or rotatable shelves in refrigerator cabinets having a food storage compartment therein of substantially rectangular form in horizontal cross section. However such shelves have had at least one of their sides so greatly cut away or omitted, to permit swinging of the shelf out of a compartment, as to be impractical in use because of the waste of valuable food storage space in a refrigerator. Some have provided a smaller auxiliary stationary shelf adjacent the omitted curved side of a swinging shelf in the rear portion of a food compartment of a refrigerator cabinet to augment the shelf supporting surface of such swingable shelves. This food supporting or storing arrangement is objectionable because of the inaccessibility of food products stored on the smaller auxiliary shelves. As far as it is known the impracticality of utilizing a swinging or rotating shelf in a refrigerator cabinet, having a food storage compartment therein which is substantially rectangular in horizontal cross section, is due to the fact that others have deemed it necessary to provide an axis point for such rotary shelves within the confines of a refrigerator cabinet in which the shelves are located. This of course restricts the area within a food storage compartment which a rotary shelf may occupy if it is to be mounted for swinging movement outwardly of a rectangularly shaped compartment.

An object of my invention is to provide an improved interior arrangement for a refrigerator cabinet so as to increase the accessibility of food products stored or supported on shelves therein.

Another object of my invention is to provide an improved combined sliding and rotating shelf within a food storage compartment of a refrigerator cabinet.

A further object of my invention is to provide an improved shelf for a refrigerator cabinet which can be moved part way out of a rectangularly shaped food storage compartment in the cabinet and yet occupies or extends across a maximum of the horizontal cross sectional area of the compartment.

A still further object of my invention is to provide an improved shelf for the food storage compartment of a refrigerator cabinet which is slidable and simultaneously rotatable by the sliding thereof about an arc having its axis disposed beyond the refrigerator cabinet structure or outside its boundary part way out of the compartment when the cabinet door is opened to render food products supported on the shelf readily accessible at the front of the cabinet.

In carrying out the foregoing objects it is a more specific object of my invention to provide means for limiting movement of a one-piece slidable and rotatable shelf outwardly of a food storage compartment of a refrigerator cabinet and to arrange the limiting means so as to be releasable whereby the shelf can be detached from

2

the cabinet and from the compartment thereof for cleaning and other purposes.

Further objects and advantages of the present invention will be apparent from the following description, reference being had to the accompanying drawings, wherein in a preferred form of the present invention is clearly shown.

In the drawings:

10 Figure 1 is a front view of a household refrigerator cabinet having a food supporting shelf constructed and arranged in accordance with my invention located in a compartment thereof;

15 Figure 2 is an enlarged horizontal cross sectional view taken on the line 2—2 of Figure 1 and showing in plan my improved shelf arrangement;

20 Figure 3 is an enlarged fragmentary sectional view taken on the line 3—3 of Figure 2 showing the shelf supported on opposed track members;

25 Figure 4 is an enlarged fragmentary sectional view taken on the line 4—4 of Figure 2 through a stationarily mounted shelf supporting track member showing a stop thereon;

30 Figure 5 is a fragmentary section taken on the line 5—5 of Figure 4 showing another view of the stationary shelf track member;

35 Figure 6 is an enlarged fragmentary sectional view taken on the line 6—6 of Figure 2 through a pivotally mounted shelf supporting track member;

40 Figure 7 is a fragmentary section taken on the line 7—7 of Figure 6 showing another view of the pivoted shelf supporting track member;

45 Figure 8 is a sectional view similar to Figure 2 on a reduced scale showing the shelf moved part way out of the food compartment in the refrigerator cabinet; and

50 Figure 9 is a sectional view similar to Figure 8 and shows the shelf in a removed position relative to the food compartment.

55 In order to illustrate my invention I have shown in Figure 1 of the accompanying drawings a household refrigerator cabinet generally represented by the reference numeral 10. Cabinet 10 includes an outer metal shell 11 and an inner metal liner 12 having insulated material disposed therebetween. The insulated walls of cabinet 10 surround a food storage compartment 14 within the cabinet. The insulated cabinet walls are polygonally arranged, as distinguished from a circular walled refrigerator, to provide a rectangular shaped food compartment which is more practical for maximum food storage space and wherein my invention is particularly adaptable.

Outer shell 11 extends downwardly below the insulated bottom wall of food compartment 14 and defines walls of a machine compartment in the lower portion of cabinet 10. A refrigerating system is associated with cabinet 10 and includes a refrigerant translating device (not shown) located in the machine compartment and an evaporator 15 mounted in food compartment 14 for cooling the interior thereof. An opening in the cabinet front wall provides access to the food storage compartment 14 and a suitably insulated door

60 17, hingedly mounted upon cabinet 10, normally closes the food compartment access opening. Conventional food supporting shelves 18 are mounted within compartment 14 and at least one food supporting shelf arrangement, generally represented by the reference numeral

65 20, constructed in accordance with my invention is also located within the compartment 14.

70 It is the purpose of my novel shelf arrangement 20 to obtain the advantages of a rotary shelf in a circular refrigerator and to provide an arrangement wherein a combined sliding and rotating shelf will occupy substantially all of the cross sectional area of a food compartment which is rectangularly shaped in horizontal cross

section. In attaining these advantages and distinguishing the present invention from shelf arrangements which are slidable only or rotatable only outwardly of a food compartment it is desired to point out that the combination of sliding and simultaneously rotating my shelf is of major importance in providing a shelf capable of occupying substantially all of the cross sectional area of a rectangularly shaped food compartment. This combination, particularly in conjunction with utilizing an axis point for a curved sided shelf that is located a substantial distance beyond the boundary or outside the refrigerator cabinet, permits the food supporting surface of a shelf to be broadened whereby only an imperceptible space is left between the curved side of a shelf and an upright wall of the food compartment in which the shelf is mounted. This imperceptible space is not objectionable from the standpoint of food storage capacity in a compartment because the minute space may be occupied by an upwardly extending outwardly inclined wall of a food receptacle supported upon the rear portion of the shelf adjacent the curved side thereof as is illustrated by the dot-dash lines in Figures 1 and 2 of the drawings. In my improved shelf arrangement the shelf itself is slidable relative to a stationary support and cooperates with this support to cause swinging of a pivotally mounted support in such a manner that the shelf is simultaneously rotated about an axis point remote from the cabinet. This is the essential feature or essence of my invention and distinguishes the present improvement over shelf arrangements wherein a shelf is slidable outwardly of a compartment and thereafter rotated or is simultaneously slid and rotated about an axis located within the confine or boundary of a cabinet. Refrigerator cabinet shelves are usually reticulated to permit cool air to pass therethrough and around food products stored thereon, thereabove, or therebelow. However, for sake of clarity in illustrating and describing the present invention I show the refrigerator shelf unreticulated and since it is of a one-piece stamped sheet metal character any desired design of reticulations may be provided in the food supporting surface thereof.

Referring now again to the drawings and particularly to Figures 2 and 3 thereof it will be noted that my one-piece sheet metal shelf 20 is provided with an upstanding rolled-over rim 21 which extends continuously from the front of the shelf around a curved side 22, a straight back side 23 and another straight side 24 thereof. The front of shelf 20 is provided with a flange 26 having a raised hand hold or handle 27 thereon preferably adjacent one side of the shelf. The side 22 of shelf 20 is curved about an arc beginning at the front of the shelf and extending to the back 23 thereof. Arcuately curved side 22 of shelf 20 has its axis located outside the boundary of cabinet 10 and in fact it can be disposed at any point beyond the confine of cabinet 10 as is desired. This point of axis is designated by the cross A and dot-dash radius line B in Figure 8 of the drawings. An elongated preferably molded plastic track member 31 is stationarily mounted by screws or the like to an upright side wall of compartment 14 adjacent its access opening. This member 31 includes a horizontal ledge or track portion 32 and an integral cover portion 33 over track portion 32 which has an opening therein adjacent the rear thereof. A lever 34 is pivotally mounted on member 31 as at 36 and has its enlarged end 37 normally biased by a spring 38 downwardly into the space between ledge 32 and cover portion 33. The end 37 of lever 34 forms or provides a stop means for limiting movement of shelf 20 outwardly of the food compartment 14. Member 31 is also provided with an integral portion 39 depending from the cover portion 33 at the front thereof to form a cam means which when shelf 20 is slid causes a second pivoted shelf supporting track member to swing about its pivotal mounting as will hereinafter be described. A second elongated preferably molded plastic track member 41 is hingedly secured, adjacent the access opening of compartment

14, to the side wall of this compartment opposite the side wall to which track member 31 is stationarily mounted. Member 41 also includes a horizontal ledge or track portion 42 and an integral cover portion 43 over track portion 42 and the edges of both portions 42 and 43 thereof are tapered inwardly toward the side wall of compartment 14, upon which member 41 is mounted, from their front to their rear end. Member 41 has integral hinge pins 44 thereon that fit into looped portions 45 at one end of a hinge wing 46 secured by screws or the like to the side wall of compartment 14 opposite the side wall thereof to which member 31 is mounted. Thus track member 41 is swingable relative to or inwardly of the wall of compartment 14 upon which it is pivotally mounted. A coil spring 47 surrounds a hinge pin 44 with its one end abutting the compartment wall, upon which member 41 is mounted, and has its other end bearing against a lug 48 integrally formed on member 41. Coil spring 47 normally biases member 41 in a direction inwardly of the upright compartment wall to facilitate swinging of this shelf supporting track member when a shelf supported thereon is moved. A shelf 20 is supported within compartment 14 on the opposed members 31 and 41 with its food supporting surface slidably resting on the track portions 32 and 42 and with the rim 21 thereof being located immediately below the covers 33 and 43 respectively as shown in Figures 3, 4, 5, 6 and 7 of the drawings so as to prevent tilting of the shelf. By reference to Figure 8 it will be seen that the axis of the radius of the curved side 22 of shelf 20 is somewhere outside the boundary of cabinet 10.

Having described the construction of my shelf arrangement and the support of shelf 20 within food compartment 14 of cabinet 10 I will now proceed to explain the manner in which it is slid and simultaneously rotated part way out of the compartment when door 17 is opened. Assume that shelf 20 is in its normal position within compartment 14 as shown in Figure 2 of the drawings and it is desired to move the shelf part way out of the compartment to render food products supported on the shelf, particularly those at the rear thereof, readily accessible at the front of cabinet 10. Door 17 is opened, as shown in Figure 8 of the drawings, and the front edge, preferably at hand hold or handle 27, is grasped by the hand of an operator and a horizontal pulling force is applied thereto. This pulling force slides shelf 20 forwardly of compartment 14 and at the same time rim 21 on the shelf engages the means or integral depending portion 39 of track member 31. This means 39 causes, while shelf 20 is being slid forwardly, member 41 to swing about its pivotal mounting, pins 44 and hinge wing loops 45, relative to and inwardly of the compartment side wall upon which member 41 is mounted. Swinging of member 41, while portion 39 of track member 31 engages the rim 21 of shelf 20, rotates the shelf simultaneously with sliding thereof about the axis A (see Figure 8) located beyond or outside the boundary of cabinet 10. Continued simultaneously sliding and rotating of shelf 20 moves same part way out of compartment 14 whereupon the stop means, end 37 of lever 34, engages a part of the shelf rim 21 at the rear side 23 of the shelf to limit this outward movement of the shelf 20 relative to compartment 14. It is to be noted, by reference to Figure 8 of the drawings, that door 17 need not be opened into a full 90° position relative to the front of cabinet 10 to simultaneously slide and rotate shelf 20 part way out of compartment 14.

The stop means, end 37 of lever 34, is releasably arranged to be moved out of the path of movement of shelf rim 21 so as to permit detachment of shelf 20 from its supports, track members 31 and 41 and removal of the shelf from compartment 14. When it is desired to remove shelf 20 for inspection or cleaning the door 17 is swung about its hinged mounting into a full 90° open position relative to the front of cabinet 10 (see Figure 9). While door 17 is opened to the 90° position the end of

lever 34 opposite its enlarged end 37 is pushed down, against the force of spring 38, to elevate its end 37 out of the path of movement of rim 21 along the rear side 23 of shelf 20. The shelf 20 can then be detached from the track members 31 and 41 and removed from compartment 14 as shown in Figure 9 of the drawings. To reposition shelf 20 into the compartment in supported relationship upon the track members 31 and 41 this removal operation is merely reversed.

It should be apparent from the foregoing that I have provided a novel and improved shelf arrangement in a refrigerator cabinet. By providing a shelf with one side having an arcuate curvature whose axis is beyond or outside the boundary of the refrigerator cabinet and by simultaneously sliding and rotating the shelf about such axis point A, in addition to rendering foods supported on the shelf readily accessible, also increase the food supporting area of a shelf in a rectangularly shaped compartment to the maximum and thereby reduce to a minimum waste space in the compartment. My arrangement retains the feature of removing a shelf from the food compartment even though means is provided to limit movement of the shelf part way out of the compartment. The simultaneous sliding and rotating shelf arrangement herein disclosed is simple in construction and inexpensive to produce.

While the form of embodiment of the invention as herein disclosed constitutes a preferred form, it is to be understood that other forms might be adopted, as may come within the scope of the claims which follow.

What is claimed is as follows:

1. The combination with a cabinet having a compartment therein provided with an access opening and a door normally closing said opening which comprises, a shelf, opposed means for slidably supporting said shelf at two sides thereof within said compartment, one of said supporting means being stationary and the other opposed supporting means being swingable, the side of said shelf supported by said stationary means being curved about an arc having its axis point located outside the boundary of said cabinet, said shelf being, when a force is applied thereto, slidably part way out of said compartment through its access opening while said door is open, and means on said stationary supporting means responsive to the sliding movement of said shelf for swinging said swingable supporting means whereby to rotate the shelf about said outside axis point simultaneously with the sliding thereof.

2. In combination, a cabinet having walls forming a compartment therein, said compartment being provided with an access opening in a wall thereof, a door normally closing said access opening, a shelf in said cabinet, a track member at two opposed walls of said compartment slidably supporting said shelf therein, one of said track members being stationarily mounted on one of said opposed compartment walls and the other of said track members being pivotally mounted on the other of said opposed compartment walls, the side of said shelf at said stationarily mounted track member being curved about an arc having its axis located outside the boundary of said cabinet, said shelf being, when a force is applied thereto, slidably along said track members part way out of said compartment through its access opening while said door is open, and means rendered effective by the sliding movement of said shelf for causing the shelf to rotate about said axis simultaneously with the sliding thereof.

3. In combination, a cabinet having walls forming a compartment therein, said compartment being provided with an access opening in a wall thereof, a door normally closing said access opening, a shelf in said cabinet, a track member at two opposed walls of said compartment slidably supporting said shelf therein, one of said track members being stationarily mounted on one of said opposed compartment walls and the other of said track members being pivotally mounted on the other of said opposed compartment walls, the side of said shelf at said sta-

tionarily mounted track member being curved about an arc having its axis located outside the boundary of said cabinet, said shelf being, when a force is applied thereto, slidably along said track members part way out of said compartment through its access opening while said door is open, and means on said stationarily mounted track member engagable by said curved side of the shelf for swinging said pivoted track member relative to the compartment wall upon which it is mounted whereby said shelf is simultaneously rotated about said axis with the sliding thereof.

4. In combination, a cabinet having walls forming a compartment therein, said compartment being provided with an access opening in a wall thereof, a door normally closing said access opening, a shelf in said cabinet, a track member at two opposed walls of said compartment slidably supporting said shelf therein, one of said track members being stationarily mounted on one of said opposed compartment walls and the other of said track members being pivotally mounted on the other of said opposed compartment walls, the side of said shelf at said stationarily mounted track member being curved about an arc having its axis located outside the boundary of said cabinet, said shelf being, when a force is applied thereto, slidably along said track members part way out of said compartment through its access opening while said door is open, means rendered effective by the sliding movement of said shelf for causing the shelf to rotate about said axis simultaneously with the sliding thereof, and means for limiting movement of said shelf outwardly of the compartment to said part way movement thereof.

5. The combination defined by claim 4 wherein the limiting means is releasable and the shelf is removable from the compartment through its access opening.

6. In combination, a cabinet having walls forming a compartment therein, said compartment being provided with an access opening in a wall thereof, a door normally closing said access opening, a shelf in said cabinet, a track member at two opposed walls of said compartment slidably supporting said shelf therein, one of said track members being stationarily mounted on one of said opposed compartment walls and the other of said track members being pivotally mounted on the other of said opposed compartment walls, the side of said shelf at said stationarily mounted track member being curved about an arc having its axis located outside the boundary of said cabinet, said shelf being, when a force is applied thereto, slidably along said track members part way out of said compartment through its access opening while said door is open, means rendered effective by the sliding movement of said shelf for causing the shelf to rotate about said axis simultaneously with the sliding thereof, and stop means on said stationarily mounted track member engageable by said shelf for limiting movement of said shelf outwardly of the compartment to said part way movement thereof, said stop means being shiftable relative to said stationary track member out of the path of movement of said shelf whereby the shelf is removable from said compartment through its access opening.

7. In combination, a cabinet having walls forming a compartment therein of substantially rectangular form in horizontal cross section, said compartment having an access opening in an upright wall thereof, a door hingedly mounted on said cabinet at one side of said compartment access opening and normally closing same, a one-piece shelf in said cabinet extending from said access opening to the rear wall of said compartment and continuously from one side to the other side walls thereof, a horizontally elongated track member pivotally mounted on the side wall of said compartment adjacent the hinged mounting of said door, a horizontally elongated track member stationarily mounted on the opposite side wall of said compartment, said track members slidably supporting said one-piece shelf within said compartment, the side of said shelf supported by said stationarily mounted track mem-

ber being curved about an arc having its axis located outside the boundary of said cabinet, said one-piece shelf being, when a horizontal force is applied thereto, slideable along said track members part way out of said compartment through its access opening while said door is open, and means rendered effective by the sliding movement of said shelf for causing the shelf to rotate about said axis simultaneously with the sliding thereof.

8. In combination, a cabinet having walls forming a compartment therein of substantially rectangular form in horizontal cross section, said compartment having an access opening in an upright wall thereof, a door hingedly mounted on said cabinet at one side of said compartment access opening and normally closing same, a one-piece shelf in said cabinet extending from said access opening to the rear wall of said compartment and continuously from one side to the other side walls thereof, a horizontally elongated track member pivotally mounted on the side wall of said compartment adjacent the hinged mounting of said door, a horizontally elongated track member stationarily mounted on the opposite side wall of said compartment, said track members slidably supporting said one-piece shelf within said compartment, the side of said shelf supported by said stationarily mounted track member being curved about an arc having its axis located outside the boundary of said cabinet, said one-piece shelf being, when a horizontal force is applied thereto, slideable along said track members part way out of said compartment through its access opening while said door is open, and means on said stationarily mounted track member engageable by said curved side of the shelf for swinging said pivoted track member relative to the compartment wall upon which it is mounted whereby said shelf is simultaneously rotated about said axis with the sliding thereof.

9. In combination, a cabinet having walls forming a compartment therein of substantially rectangular form in horizontal cross section, said compartment having an access opening in an upright wall thereof, a door hingedly mounted on said cabinet at one side of said compartment access opening and normally closing same, a one-piece shelf in said cabinet extending from said access opening to the rear wall of said compartment and continuously from one side to the other side walls thereof, a horizontally elongated track member pivotally mounted on the side wall of said compartment adjacent the hinged mounting of said door, a horizontally elongated track member stationarily mounted on the opposite side wall of said compartment, said track members slidably supporting said one-piece shelf within said compartment, the side of said shelf supported by said stationarily mounted track member being curved about an arc having its axis located outside the boundary of said cabinet, said one-piece shelf being, when a horizontal force is applied thereto, slideable along said track members part way out of said compartment through its access opening while said door is open, means rendered effective by the sliding movement of said shelf for causing the shelf to rotate about said axis simultaneously with the sliding thereof, and means on said stationarily mounted track member engageable by said curved side of the shelf for swinging said pivoted track member relative to the compartment wall upon which it is mounted whereby to rotate said shelf about said axis simultaneously with the sliding thereof.

10. In combination, a cabinet having walls forming a compartment therein of substantially rectangular form in horizontal cross section, said compartment having an access opening in an upright wall thereof, a door hingedly mounted on said cabinet at one side of said compartment access opening and normally closing same, a one-piece shelf in said cabinet extending from said access opening to the rear wall of said compartment and continuously from one side to the other side walls thereof, a horizontally elongated track member pivotally mounted on

the side wall of said compartment adjacent the hinged mounting of said door, a horizontally elongated track member stationarily mounted on the opposite side wall of said compartment, said track members slidably supporting said one-piece shelf within said compartment, the side of said shelf supported by said stationarily mounted track member being curved about an arc having its axis located outside the boundary of said cabinet, said one-piece shelf being, when a horizontal force is applied thereto, slideable along said track members part way out of said compartment through its access opening while said door is open, means rendered effective by the sliding movement of said shelf for causing the shelf to rotate about said axis simultaneously with the sliding thereof, means on said stationarily mounted track member engageable by said curved side of the shelf for swinging said pivoted track member relative to the compartment wall upon which it is mounted whereby to rotate said shelf about said axis simultaneously with the sliding thereof, and means for limiting movement of said shelf outwardly of the compartment to said part way movement thereof.

11. In combination, a cabinet having walls forming a compartment therein of substantially rectangular form in horizontal cross section, said compartment having an access opening in an upright wall thereof, a door hingedly mounted on said cabinet at one side of said compartment access opening and normally closing same, a one-piece shelf in said cabinet extending from said access opening to the rear wall of said compartment and continuously from one side to the other side walls thereof, a horizontally elongated track member pivotally mounted on the side wall of said compartment adjacent the hinged mounting of said door, a horizontally elongated track member stationarily mounted on the opposite side wall of said compartment, said track members slidably supporting said one-piece shelf within said compartment, the side of said shelf supported by said stationarily mounted track member being curved about an arc having its axis located outside the boundary of said cabinet, said one-piece shelf being, when a horizontal force is applied thereto, slideable along said track members part way out of said compartment through its access opening while said door is open, means rendered effective by the sliding movement of said shelf for causing the shelf to rotate about said axis simultaneously with the sliding thereof, means on said stationarily mounted track member engageable by said curved side of the shelf for swinging said pivoted track member relative to the compartment wall upon which it is mounted whereby to rotate said shelf about said axis simultaneously with the sliding thereof, means for limiting movement of said shelf outwardly of the compartment to said part way movement thereof, and said last named means being releasable whereby said shelf is removable from said compartment through its access opening.

12. The combination with a cabinet having a compartment therein provided with an access opening and a door normally closing said opening which comprises, a shelf, means for mounting said shelf within said compartment, one side only of said shelf being curved from a point adjacent the front thereof toward its back about an arc having its axis located outside the boundary of said cabinet, said mounting means including a stationary means supporting said curved side of the shelf for sliding movement outwardly of said compartment when said door is opened, and said mounting means also including a means both pivotally and slidably supporting the side of said shelf opposite its curved side for causing the shelf to be rotated simultaneously with sliding thereof about said outside axis.

13. The combination with a cabinet having a compartment therein provided with an access opening in the front thereof and a door hingedly mounted on the cabinet for horizontal swinging movement normally closing said opening which comprises, a shelf, means for mounting said shelf within said compartment, one side only of

said shelf remote from the hinged mounting of said door being curved from a point spaced inwardly of its front toward the back thereof about an arc having its axis located outside the boundary of said cabinet whereby the shelf occupies the major portion of the horizontal cross sectional area of said compartment, said mounting means including a stationary means on the side of said cabinet opposed to the side thereof upon which said door is mounted supporting said curved side of the shelf for sliding movement outwardly of said compartment when said door is opened, and said mounting means also including a means on said cabinet at the hinged side of said door

both pivotally and slidably supporting the side of said shelf opposite its curved side for causing the shelf to be rotated simultaneously with sliding thereof about said outside axis.
